UNITED STATES PATENT OFFICE.

MORRIS NOVER, OF JERSEY CITY, NEW JERSEY.

HAND-BAG HANDLE.

Application filed October 28, 1925. Serial No. 65,401.

This invention relates to handbags, and more particularly to handles therefor of the type adapted to be expanded to form a carrying loop or contracted flat against the bag. The objects of the invention are to simplify the construction of handles of this type and to render them more durable and also neat and trim in appearance.

In the drawings, Fig. 1 is a front face view of a handbag equipped with the improved handle;

Fig. 2 a top plan view of the bag and handle;

Fig. 3 a plan view of one of the handle straps;

Fig. 4 a fragmentary view of the under face of the companion strap;

Fig. 5 an enlarged longitudinal sectional view of the handle, showing it contracted or flattened;

Fig. 6 a transverse section taken on the line 6—6 of Fig. 7;

Fig. 7 an edge view of the handle with the straps flattened;

Fig. 8 a longitudinal sectional view of a modified form of handle;

Fig. 9 an edge view of the handle shown in Fig. 8; and

Fig. 10 a plan view thereof.

Referring to the parts in detail, B represents the body of a handbag of conventional form. The bag is formed with a closure flap F which folds over the top or mouth of the bag and down over the front face thereof, to which it is secured by a snap fastening. The handle H is formed of two flat, flexible straps 1 and 2 of equal length. Each of these straps has one of its ends stitched as at 3 to the top fold or bend 40 of the flap F, at points located near the opposite ends of the bag. From their points of attachment 3 the straps extend toward each other and overlap longitudinally over the center of the bag. The inner or overlapped ends of the straps are flared outwardly or widened as at 4. The strap 1 overlies the strap 2 and the widened end 4 of the underlying strap 2 projects out beyond the opposite side edges of the strap 1, as will be seen in Figs. 2 and 6. A loop-forming cap piece 5 is stitched as at 6 to the oppositely projecting side edges of the widened end of the strap 2, and extends transversely across the outer face of the strap 1. The piece 5 forms, with the widened end of the strap 2, a guide loop

through which the strap 1 is adapted to slide. The piece 5 is flat, preferably made of the same material as the straps and cut at one end so as to extend from the end 4 of the attached strap in the form of a point 7, and curved outwardly at its opposite end as at 8 to extend beyond its points of attachment 6 with the strap. The end 4 of the strap is also curved outwardly beyond the ends of the stitching as indicated at 8'. These curved ends of the cap piece and strap form oppositely extending lips adapted to frictionally engage the inner and outer faces of the strap 1 passing between them.

The widened end of the overlying strap 1 is slit transversely as at 9 to form a guide loop through which the underlying strap 2 is adapted to slide. Stitched at 10, directly to the opposite side edges of the widened end of the strap 1, is a shield piece or cap 11. This piece is a duplicate of the loop-forming piece 5 and is disposed to overlie and conceal the transverse slit 9. The cap pieces 5 and 11, being similarly formed, give a balanced and symmetrical appearance to the handle.

In the modification shown in Figs. 8, 9, and 10 the handle is formed in the same manner as the form just described, with the exception of the guide loop through which the underlying strap 2 slides. The manner of forming this loop is shown at the right, with reference to the drawings. The widened end 4 of the overlying strap 1 is not slit to form a loop as in the previous form. A flat loop-forming piece 12, similar to the piece 5 at the left, is secured to the under face of the widened end of the strap 1 at opposite sides thereof by stitches 13. This piece 12 forms, with the widened end of the strap, the guide loop through which the under strap 2 is adapted to slide.

It will be seen from the drawings and description that a neat, durable and easily constructed handle is provided. The loop-forming parts add to the attractiveness of the handle and are designed to withstand hard wear. The manner of forming the loops greatly simplifies their manufacture, it being merely necessary to stitch the wide transverse pieces to the widened ends of the straps in order to form the loops. The loops so formed are flat and thin so that the entire handle will lie flat against the bag when it is contracted. The loop-forming pieces are of material length and are stitched in place

so that they will snugly engage the straps passing through the loops formed by them, and will offer a certain amount of frictional resistance to their sliding. The straps will therefore tend to remain flat when collapsed.

What I claim is:

1. A handle for a handbag, comprising a pair of flat flexible straps overlapping each other longitudinally for a portion of their length at and adjacent one end of each strap, the opposite outer ends of the straps being adapted to be attached to the handbag and the ends of the overlapped portions being wider than the adjacent overlapped portion of the other strap; a flat loop-forming cap piece stitched to the face of one of said wider ends along the opposite side edges thereof and extending transversely across the opposed strap to form a relatively slid-
able guide loop therefor, the other of said wider ends being formed with a transverse slit adapted to permit the opposed strap to slide through it; and a shield-piece shaped similarly to the said loop-forming piece and stitched to the face of the widened end containing the said slit, the said shield-piece extending over and covering the slit.

2. A handle for a handbag comprising a pair of flat flexible straps overlapping each other longitudinally for portions of their lengths at an adjacent one end of each strap, the opposite outer ends of said straps being adapted to be attached to the handbag, and the end of one of said overlapped portions being wider than the adjacent overlapped portion of the other strap; a flat loop-forming cap piece stitched to a face of the said wider end along the opposite side edges

thereof and extending transversely across the overlapped strap to form a relatively 40
slidable guide loop therefor, the strap end and cap piece forming said loop extending in opposite directions beyond the ends of said stitching to form lips adapted to frictionally engage the opposite faces of the 45
strap trained through the loop; and guide means slidably connecting the other of said overlapping strap portions to its opposed strap.

3. A handle for a handbag comprising a 50
pair of flat flexible straps overlapping each other longitudinally for portions of their lengths at and adjacent one end of each strap, the opposite outer ends of said straps being adapted to be attached to the hand-
bag, and the end of one of said overlapped portions being wider than the adjacent overlapped portion of the other strap; a flat loop-
forming cap piece stitched to one face of the said wider end along the opposite side edges 60
thereof and extending transversely across the overlapped strap to form a relatively 65
slidable guide loop therefor, the opposite ends of said cap piece extending respectively inwardly and outwardly longitudinally of
the straps beyond the ends of said stitching and the inwardly extending end of the cap piece forming a lip adapted to frictionally engage one face of the strap trained through the loop; and guide means slidably connecting the other of said overlapping strap portions to its opposed strap.

In testimony whereof I hereunto affix my signature.

MORRIS NOVER.
